UNITED STATES PATENT OFFICE.

ROBERT E. WALLISER, OF CHICAGO, ILLINOIS, ASSIGNOR TO H. F. WALLISER COMPANY, OF CHICAGO, ILLINOIS, A CORPORATION OF ILLINOIS.

ATTACHING DEVICE FOR PICTURE AND MIRROR CORDS.

Application filed November 20, 1924. Serial No. 751,035.

To all whom it may concern:

Be it known that I, ROBERT E. WALLISER, a citizen of the United States, residing in Chicago, Illinois, have invented certain new and useful Improvements in Attaching Devices for Picture and Mirror Cords, of which the following is a specification.

In recent years it has become quite fashionable to dispense with picture molding in the building of homes and in order to hang pictures or mirrors, it is necessary, where there is no picture molding, to drive a nail into the wall from which the picture or mirror is hung. This has caused some confusion in the sale of picture and mirror cords, especially of the type now in style where twisted cords are employed which depend from rosettes or similarly ornamental devices, since devices with a picture molding hook thereon cannot be employed where there is no picture molding in the room. The dealer, therefore, has found it necessary to carry two stocks of picture and mirror cords, one equipped with hooks and the other equipped with metal rings in place of a hook.

To overcome the above conditions, I have invented an attaching device for picture and mirror cords which can be used either for suspending a picture or mirror from a molding or from a nail or similar device which is secured to the wall; my improved attaching device including a hook portion which is capable of supporting the same from a molding. This hook portion is of such construction that it can be readily detached from another part which includes an aperture capable of engaging over a nail or other device which is driven into the wall if it is desired or necessary to suspend the cord from a nail or other device which is driven into the wall.

Another advantage of my improved structure is that the hook portion is so constructed and associated with the other portion that it cannot become accidentally detached.

Another object is to make my improved attaching device of a durable construction capable of holding a picture or mirror of great weight.

The above objects and other advantageous ends which will be set forth hereinafter, I attain in the following manner, reference

being had to the accompanying drawing in 55 which

Figure 1 is a front view of a picture or mirror cord depending from an ornamental rosette, the back of which is equipped with my improved attaching device. 60

Figure 2 is a side elevation of Figure 1 illustrating my invention,

Figure 3 is a rear view showing my invention,

Figures 4 and 5 are views of the same 65 general character as shown in Figure 3 illustrating different positions of the picture molding hook portion which it assumes when detaching the same.

Figure 6 is a rear view showing the same 70 after the molding hook portion has been detached therefrom, and

Figures 7, 8 and 9 are detail views showing the picture molding hook portion of the device. 75

Referring to the drawing, 10 represents an ornamental member, such as a rosette, having a backing 11 to which is attached the leg 12 of a securing member 13. This securing member is attached to the backing 11 80 by a screw 14 and may be made of strip metal as clearly illustrated in Figures 2 and 6 of the drawing. The member 13 is bent or otherwise formed to produce an upwardly extending leg 15 which is spaced from the leg 12 and has a hole or aperture 16, the hole being of greater width at the top than at the bottom. The lower portion 17 of the member 13 has a hole 18 through which the picture or mirror cord 19 extends, said cord 90 preferably being folded, as shown at 20, with the folded portion squeezed between the legs 12 and 15. A hook member 21, the details of which are shown in Figures 5, 8 and 9 has an arcuate portion 22 which at one end is provided with an angular portion 23 of reduced width. This angular portion 23 joins with an enlarged tongue 24.

In joining the member 21 to the member 13, the tongue 24 can be slipped lengthwise 100 through the hole 16 as shown in Figure 5 and the member 21 can then be rocked so that the portion 23 can also enter the hole 16. The member 21 can then be slightly raised into the position shown in Figure 4 105 and then turned into the position shown in Figure 3; the reduced portion 23 extending transversely across the hole 16 with

the tongue 24 overlapping the inner surface of the leg 15. In this latter position, as shown in Figures 2 and 3, the device can be used for suspending the cord from a picture molding.

- If it is desired to suspend the device from a nail or hook in the wall, the member 21 can be detached from the member 13 by reversing the movements just described. This 10 allows the member 21 to be entirely removed from the device, as shown in Figure 6, and the aperture 16 allows the device to be suspended from a nail or hook in the wall with the head of the nail extending through the 15 aperture 16.

I preferably round or bevel the portion 25 of the tongue 24 to facilitate the rocking of the member 21, as above mentioned, to allow the portion 23 to freely enter or withdraw from the aperture 16. By providing the part 13 with the hole 16 and the part 20 21 with the tongue 24 as described and illustrated, the parts will be interlocked against accidental separation when in use since it 25 requires more than relative vertical movement to effect the separation of said parts. I preferably make the cord 19 with the wire core and it will be noted that when the 30 cord is folded as above stated that it will be impossible for it to pull out of the hole 18.

In this application I have shown but not claimed certain features, said features being claimed in my co-pending application for United States Patent for attaching devices 35 for picture and mirror cords, Serial No. 13,811, filed March 7th, 1925.

Having thus described my invention what I claim as new and desire to secure by Letters Patent is:

- 40 1. An attaching device for picture and mirror cords including two parts, one of said parts being operative to directly support a suspension cord and having a hole therein, the other of said parts including a 45 moulding-engaging hook and a tongue, with a portion connecting the tongue with the hook, said tongue being adapted to be projected through said hole and being of such width as to overlap opposite walls of

the hole at the back of said first part with 50 said connecting portion in said hole, whereby said parts will be interlocked against accidental separation.

2. An attaching device for picture and mirror cords including two parts, one of 55 said parts having a portion operative to secure a cord independently of the other part, said first mentioned part having an aperture, said other part having a moulding-engaging hook with an angular portion 60 extending therefrom, said latter part having a tongue projecting angularly from said first mentioned angular portion and being of greater width than said first angular portion whereby it can be projected through 65 said aperture in the direction of its height to allow the first mentioned angular portion to enter said aperture and be turned therein, said tongue being of such width as to overlap the side edges of said aperture and thereby effect the securing of said two parts together.

3. An attaching device for picture and mirror cords including a part providing a hole through which a cord can be projected, 75 said part having a lower bend with upwardly extending leg portions capable of squeezing together the part of said cord projected through said hole, said part having a portion for suspension from a supporting nail 80 or hook, and a second part connected to said first part and having a moulding-engaging portion thereon whereby the entire device can be suspended from a moulding.

4. A device of the character described in- 85 cluding cord-suspending parts detachably connected together, one of said parts including a hook whereby the entire structure can be suspended from a wall moulding, the other part having a portion for suspending 90 the cord independently of the hook, said latter part having a portion for attachment to an ornamental facing member whereby the latter will obscure from view the connection between said parts.

In testimony whereof I have signed my name to this specification.

ROBERT E. WALLISER.
